CLAIM

The ornamental design for a cover for vehicle storage compartment, as shown and described.

DESCRIPTION

FIG. 1 is a side view of a cover for vehicle storage compartment constructed exterior surface constructed in accordance to the teachings of the present shown in a closed position and illustrated on a pickup truck between the bed and the cab of the pickup truck;

FIG. 2 is an enlarged rear and side perspective view of the vehicle storage compartment exterior surface shown in FIG. 1, it being understood that the front side is a mirror image of the rear side;

FIG. 3 is an enlarged side view of the vehicle storage compartment exterior surface shown in FIG. 1; and,

FIG. 4 is a greatly enlarged top view of the vehicle storage compartment exterior surface in FIG. 1.

The broken lines shown in all views of the drawing are for illustrative purposes only and form no part of the claimed design.
